HARRY Y. ARMSTRONG, OF SPRINGFIELD, MASSACHUSETTS, ASSIGNOR TO UNITED SEALING MACHINE COMPANY, OF SPRINGFIELD, MASSACHUSETTS, A CORPORATION OF MASSACHUSETTS.

ENVELOP-SEALING MACHINE.

1,269,671.

Specification of Letters Patent. Patented June 18, 1918.

Application filed June 11, 1917. Serial No. 174,138.

To all whom it may concern:

Be it known that I, HARRY Y. ARMSTRONG, a citizen of the United States of America, residing at Springfield, in the 5 county of Hampden and State of Massachusetts, have invented certain new and useful Improvements in Envelop-Sealing Machines, of which the following is a specification.

10 This invention relates to envelop sealing machines and more particularly to improvements in sealing machines of the type disclosed in the patent to Davis, No. 1,139,499, dated May 18, 1915.

15 An object of the invention is to provide in a machine of the class described, a rotatable head carrying means adapted to moisten the flaps of the envelops and improved devices separate from the head to intermittently supply moistening fluid to said means,

20 characterized by the separation of the moistening means from the supply for more uniform and efficient moistening of said means.

25 Other objects and advantages will appear in the following description and will be particularly pointed out in the appended claims.

The invention, in an embodiment at present preferred, is shown for illustrative purposes, in the accompanying drawings, in which—

30 Figure 1 is a plan view of the sealing machine with certain parts broken away;

35 Fig. 2 is a side elevational view thereof;

Fig. 3 is a perspective view showing in detail a part of the receiving magazine;

40 Fig. 4 is a fragmentary elevational view of the yieldable keepers for the receiving magazine;

Fig. 5 is a sectional elevation taken on the line 5—5 of Fig. 1;

45 Fig. 6 is a fragmentary longitudinal section of the machine, taken on the line 6—6 of Fig. 1;

Fig. 7 is an enlarged detail view of a part of Fig. 6; and

50 Fig. 8 is a sectional view taken similar to Fig. 6, showing certain parts of the latter in different relative positions.

Referring to these drawings in detail, the frame of the machine is indicated at A.

The motive power of the machine may consist advantageously of a suitable electric

motor B, mounted on the lower part of 55 frame A. Mounted in frame A in a manner to be later described in detail are the following elements,—a magazine to receive envelops to be sealed, a movable moistening device to moisten the gummed flaps of the 60 envelops, a means for intermittently supplying fluid to the moistening device, sealing rolls to press the moistened flaps to the envelop body, a reciprocable slide to successively deliver envelops to the sealing rolls, 65 yieldable keepers associated with the receiving magazine to control the removal of envelops therefrom, a delivery magazine, and devices to take sealed envelops from the rolls and stack them upon the delivery 70 magazine.

The receiving magazine comprises two laterally spaced side plates 10 and two relatively short rear guides 11, one of which is shown in Fig. 3. Plates 10 have upwardly and forwardly curved portions provided with inturned flanges 13 to engage the front edge of the envelops, and the rear guides 11 are flanged as shown in Figs. 1 to 3 to rest upon the rear parts of plates 10. Guides 75 11 are adjustably held to the latter by screws 14 which are movable in suitable slots in plates 10, as shown in Fig. 2, to permit envelops of varying widths to be accommodated between the guides 11 and 80 flanges 13. The plates 10 are slidably mounted on a cross rod 15 secured to frame A and may be held to the rod in various positions of axial adjustment thereon by set screws 16, whereby envelops of varying 85 lengths may be accommodated. The rear guides 11 have at their lower ends inturned and forwardly extending flanges 17 (Figs. 1 and 3) to support the lowermost envelop d in the receiving magazine along its rear 90 edge, as clearly shown in Fig. 6. The lowermost envelop d is supported along its forward edge by a plate 18 which extends transversely across the frame A and is suitably secured thereto. The central portion of 95 plate 18 is bent downwardly to permit the flap d' of the lowermost envelop to open as indicated in Fig. 6 and, to further assist in opening the flaps d', the envelops are so supported that they incline downwardly to 100 ward the plate 18.

The described flange 13 for engaging the front edge of envelops d is cut away near

the lower part of the plate to permit envelops to be delivered in a forwardly direction (to the right) from the magazine. Near the forward lower part of the latter 5 means are provided to restrain all but the lowermost envelop *d* from forward movement. These means comprise brushes 19 (Figs. 4 and 6) which are slideable upon a rectangular cross bar 20 with a sufficient 10 amount of friction so that they remain in any of the positions to which they may be moved. Bar 20 extends transversely across frame A and is mounted thereon for vertical adjustment. The ends of bar 20 have 15 slots 21 therein (Fig. 4) to receive retaining bolts 22 (Fig. 2) which hold the bar to the frame for vertical movement in an obvious manner. The frame of each brush 19 has a backing plate 23 secured thereto which 20 extends downwardly toward the lower ends of the brushes and terminates at a distance from the lower ends of the latter substantially equal to the thickness of the thickest envelop which would ordinarily be handled. 25 The plates 23 function to prevent a plurality of envelops from engaging the brushes if by chance other envelops above the lowermost should be carried therewith by frictional engagement when the latter is 30 withdrawn in a manner to be described. The brushes are adjusted by raising or lowering bar 20, so that their lower edges are spaced from plate 18, a distance only slightly less than the thickness of the envelop. Thus, 35 only a slight, although effective, resistance is presented to the lowermost envelop so that it may be removed from the magazine without great effort. The bristles yield as the envelop is pushed forwardly and lightly 40 brush across the envelop, as distinguished from a rigid keeper which does not yield and has to be cammed upwardly by the envelop itself to the detriment of the latter.

The means for moistening the gummed 45 flaps *d'* comprises a head or disk 25 which is pinned (Fig. 6) to the upper end of a vertical shaft 26 and which is rotatable in a horizontal plane and substantially in the plane of the gummed flap *d'* of the lowermost envelop. Shaft 26 is mounted in suitable brackets attached to frame A and bears at its lower end a worm wheel 27 (Fig. 2) which in turn meshes with a worm 28 on one end of the shaft of motor B. Substantially 50 half of the periphery of disk 25 is concentric with its axis and about this portion of its periphery is a strip of felt 29 or other suitable absorbent material which is secured to the under face of the disk and 55 protrudes concentrically beyond the periphery of the latter. The outer and lower edge of felt 29 is beveled at an angle substantially the same as that assumed by the open flap *d'* and, as the disk 25 is rotated, the 60 65 beveled portion of the strip wipes across the

gummed flap covering all portions of the latter as will appear. Felt 29 is more or less saturated with water, being intermittently supplied by means to be described, and therefore moistens the gummed flap *d'*. 70

The means for moistening felt 29 will next be described. Adjacent one side of frame A and suitably secured thereto is a container 30 which, as shown in Fig. 5, is formed with a chamber 31 and a well 32 75 connected to the latter by an opening 33. Above the well 32 is a cylindrical supply tank 34 which extends transversely across the rear of the machine and is removably supported, as shown in Fig. 2, by pins 35 which 80 loosely rest in brackets secured to and extending upwardly from frame A. Tank 34 has been shown as removed from Fig. 1 to reveal parts thereunder. Referring to Fig. 5, an outlet pipe 36 is threaded into the 85 lower part of the tank and depends into well 32. Pipe 36 may be raised and lowered in the well by turning the pipe by the knurled portion provided, and may be held in various positions of vertical adjustment 90 by a check nut 37. Tank 34 has no air vent other than pipe 36, and it will be obvious that fluid from the tank will flow into well 32 only when the level of the water in the latter falls below the bottom of pipe 36. 95 Thus, the level in well 32 and chamber 31 may be automatically maintained substantially constant and the level may be varied when desired by raising or lowering pipe 36. Extending loosely through the latter is a 100 stem 38, the lower end of which is normally supported on the bottom of well 32 as shown. On the upper end of stem 38 is a valve 39 which is normally held away from its seat in the tank to permit fluid to flow therefrom, 105 but, when tank 34 is lifted out of its supporting brackets, valve 39 automatically closes by gravity and stops the flow of fluid.

The well 32 supplies the chamber 31 and in the latter is a spherical float 40 which may 110 be a rubber ball, for example. Float 40 is ordinarily forced against the conical top of the container by the fluid. Container 30 has a slot 41 therein through which the felt 29 on the described disk 25 is movable to engage 115 the float 40. The felt 29 is arranged to force the float downwardly a slight amount as it first engages therewith and thereafter to turn the float so that a freshly moistened surface is always presented to the felt. Float 120 40 may be roughened as shown, or it may be smooth, but the illustrated construction is preferred since a plurality of pockets are formed which will more effectually carry the water to the felt. It will thus be seen that 125 at each revolution of disk 25 the entire surface of felt 29 is moistened, and the degree of moistening may be varied by varying the fluid level in chamber 31.

Referring to Figs. 1 and 2, slidably sup- 130

ported on a pair of spaced rods 42 secured in parallel relation to frame A is a carriage 43 which is reciprocable by a connecting rod 44 (Figs. 1 and 6), the latter being actuated by a crank 45 on the described shaft 26. Secured to and extending forwardly from carriage 43 in spaced parallel relation are a pair of thin blades 46 which are movable just above the upper surface of disk 25 and are guided between a central circular boss on the disk 25 and a disk 47 held thereto as shown in Fig. 6. Blades 46 engage between the body of the envelop *d* and the gummed flap *d'* and transfer the envelop to the sealing means. The rotatable moistening device and the reciprocable feeding device are covered by plates *c* which extend across the tops of frame A (Fig. 2). These plates have been purposely omitted in Fig. 1 to reveal the devices therebelow.

The sealing means comprises two preferably rubber covered rolls 48 which are mounted one above the other adjacent the forward part of the receiving magazine. The upper roll 48 is slidable vertically in frame A and is forced against the lower roll by coiled springs 49 in the usual well known manner. Both rolls are connected by intermeshing gears 50 arranged just inside one of the frames A. The lower roll 48 is driven by a gear train 51 from a shaft 52. The envelops, delivered into the bight of rolls 48 by blades 46, are carried between the rolls to seal the flap *d'* to the envelop, and the sealed envelops are delivered from the rolls to a stacking device.

The latter comprises two disks 53 (Figs. 1, 6, and 8) which are slidably keyed to sleeves 54 as shown in Fig. 8 and may be held in various positions of axial adjustment thereon by screws 55. The sleeves 54 are loosely mounted on the described shaft 52 and may be held thereto by screws 56 (Fig. 1). Sleeves 54 may be angularly adjusted relatively to shaft 52 by loosening screws 56 and turning the sleeves. The shaft 52 is connected by bevel gears 57 to a vertical shaft 58 (Fig. 6) and on the lower end of the latter is a worm wheel 59 (Fig. 2), which is driven by a worm (not shown) on the motor B. Thus, the disks 53 may be continuously driven.

Between the disks 53 and above shaft 52 is a table 60 (Figs. 1 and 6) which has a downwardly bent forward face 61 (Fig. 6). Secured to frame A and extending from the lower end of member 61 forwardly with a slight upward inclination are a pair of spaced parallel plates 62. Slidable upon the latter is a carriage 63 which has a central upstanding finger 64 angularly adjustable relatively to the carriage. The latter tends to move by gravity into such a position that the finger 64 abuts the part 61, and the sealed envelops are adapted to be received

therebetween. The carriage 63, plates 62, and member 61 constitute the delivery magazine for the envelops.

The disks 53, one on each side of table 60, are spaced just sufficiently to receive therebetween the envelops *d*. Extending from each disk 53 toward table 60 is a flange which starts from the center of the disk with a straight portion 65 and then extends spirally as at 66 toward the outer periphery of the disk and terminates by doubling back on the spiral portion with a straight portion 67 which is arranged nearly at right angles to the portion 65. When the envelop *d* leaves rolls 48, disks 53 are positioned, as shown in Fig. 8, so that flange 67 forms with the upper surface of table 60 an open ended slot 68. The envelops *d* are thrown from the rolls 48 at high speed into slot 68 and travel into the position shown in Fig. 8, wherein they are positioned both laterally and longitudinally. As disk 53 rotates, the flange 67 holds the envelop *d* from leaving the table and eventually the flange 65 engages the envelop from below, tipping the rear end thereof. As the rear end of the envelop is tipped, the flange 67 gradually withdraws from engagement with the envelop allowing the latter on continued tipping to slide over the forward edge of table 60 upon the members 62. The flanges 66 hold back the stack of envelops on members 62 so that the incoming envelop can freely pass to the latter as described. Continued rotation of the disks permit the flanges 65 to bring the envelop into substantially vertical position with its rear face substantially contiguous to the member 61. As the incoming envelop is thus positioned, the previously stacked envelops are released from the large ends of flanges 66 and fall back into engagement with the incoming envelop by the force exerted by carriage 63. Shortly thereafter, the small ends of flanges 66 engage the stack of envelops and move them forwardly away from plate 61 to permit another envelop to be delivered on members 62 as described.

The operation of the machine will be briefly described. As the motor B is energized, the disk 25 is revolved. The edge of disk 25 in advance of the felt, that is the part of disk 25 which first engages the flap of the envelop, is formed with a knife edge to enter between the envelop and flap and cam the latter open if it tends to stick. This action prepares the flap for the application by the felt of water to the gum. The felt 29 on disk 25 is moistened intermittently once each revolution by the float 40 as described. The forward end of felt 29 engages the rear end of the gummed portion of flap *d'* of the lowermost envelop *d* in the stack and wipes across the gummed portion to moisten it. After the forward por-

tion of felt 29 has engaged and moistened the rear gummed portion of flap d' , the fingers 46 engage the envelop between the flap and body and commence to move it toward 5 the feeding rolls. During the latter movement, other portions of the felt 29 sweep across the flap, moistening new portions of the flap as the latter is withdrawn until all the gummed portions are thoroughly moistened. The envelop then is taken into the bight of rolls 48 and in traveling therethrough the moistened flap d' is firmly pressed to the body of the envelop. The sealed envelops are thrown upon table 60 10 and are removed therefrom and stacked 15 upon the plates 62, as already described.

An important feature of the invention is the separation of the moistening felt from the fluid supply therefor. The revoluble 20 moistener disk 25 can thereby be made of much lighter construction than that disclosed in the Davis patent above referred to. The troubles due to carrying water in a moving part of the machine are also 25 eliminated. Furthermore, the fluid is supplied to the felt in a uniform and regulable manner. It is not necessary for the fluid to work its way through a mass of absorbent material by capillary action to reach the 30 surface effective for moistening the envelops with the possibility of clogging from various sources. On the contrary, the fluid is applied directly to that portion of the absorbent material which will engage the 35 gummed flap of the envelop, and the amount of fluid applied may be regulated within narrow limits. The various parts of the fluid supplying devices are exposed for ready inspection and adjustment, and the 40 operator can quickly detect and remedy troubles due to insufficient or excessive moistening without waiting for the envelops to be delivered from the machine imperfectly sealed.

45 The invention has been described in a preferred form for illustrative purposes, but the scope of the invention is defined by the appended claims rather than by the foregoing description.

50 What I claim is—

1. An envelop sealing machine, comprising in combination, means to support an envelop for free extension of the flap thereof angularly relatively to its body, a head rotatable on an axis substantially perpendicular to the plane in which the envelop body is supported and provided with a beveled marginal portion having absorbent material on part of such portion adapted to 55 extend between the projecting flap of the envelop and its body to moisten the gummed portion of the flap by engagement therewith, means to press the moistened flap to the body of the envelop to seal the latter, means to carry the envelop from its sup-

porting means to the sealing means, and means intermittently engageable by said head to supply moistening fluid to the absorbent marginal portion thereof.

2. An envelop sealing machine, comprising in combination, means to support an envelop for free extension of the flap thereof angularly relatively to its body, a head rotatable on an axis substantially perpendicular to the plane in which the envelop body is supported and provided with a beveled marginal portion partly of absorbent material adapted to extend between the projecting flap of the envelop and its body to moisten the gummed portion of the flap by 75 engagement therewith, means to press the moistened flap to the body of the envelop to seal the latter, means to carry the envelop from its supporting means to the sealing means, a container for moistening fluid arranged in the path of said absorbent portion, and means in the container engageable intermittently by said absorbent portion and adapted to be moved by the latter to convey fluid from the container to said portion. 90

3. An envelop sealing machine, comprising in combination, means to support an envelop for free extension of the flap thereof angularly relatively to its body, a head rotatable on an axis substantially perpendicular to the plane in which the envelop body is supported and provided with a beveled marginal portion partly of absorbent material adapted to extend between the projecting flap of the envelop and its body to 95 moisten the gummed portion of the flap by engagement therewith, means to press the moistened flap to the body of the envelop to seal the latter, means to carry the envelop from its supporting means to the sealing means, a container for moistening fluid arranged in the path of said absorbent portion, a ball float in the container engageable intermittently by said absorbent portion and adapted to be moved by the latter to convey fluid from the container to said portion. 100

4. An envelop sealing machine, comprising in combination, means to support an envelop for free extension of the flap thereof angularly relatively to its body, a head rotatable on an axis substantially perpendicular to the plane in which the envelop body is supported and provided with a beveled marginal portion of absorbent material adapted to extend between the projecting flap of the envelop and its body to 105 moisten the gummed portion of the flap by engagement therewith, means to press the moistened flap to the body of the envelop to seal the latter, means to carry the envelop from its supporting means to the sealing means, a container for moistening fluid arranged in the path of said absorbent portion, a ball float in the container engageable intermittently by said absorbent portion and adapted when the float is turned to 110 convey fluid from the container to said portion, a tank for containing a supply of fluid, and means connecting the tank and container so that the former may feed the latter and so that the fluid level in the container is maintained substantially at a constant level. 115

5. An envelop sealing machine, comprising in combination, means to support an envelop for free extension of the flap thereof angularly relatively to its body, a head rotatable on an axis substantially perpendicular to the plane in which the envelop body is supported and provided with a beveled marginal portion of absorbent material adapted to extend between the projecting flap of the envelop and its body to 120 moisten the gummed portion of the flap by engagement therewith, means to press the moistened flap to the body of the envelop to seal the latter, means to carry the envelop from its sup-

to seal the letter, means to carry the envelop from its supporting means to the sealing means, a container for moistening fluid arranged in the path of said absorbent portion, and a ball float in the container engageable intermittently by said absorbent portion and adapted to be turned by the latter to convey fluid from the container to said portion, a tank for containing the

moistening fluid, a single outlet pipe therefrom depending into said container and spaced above the bottom of the latter, whereby the fluid level in the container may be maintained substantially constant, means to move the pipe relatively to the container to vary the level of the fluid therein.

HARRY Y. ARMSTRONG.

Copies of this patent may be obtained for five cents each, by addressing the "Commissioner of Patents, Washington, D. C."

It is hereby certified that in Letters Patent No. 1,269,671, granted June 18, 1918, upon the application of Harry Y. Armstrong, of Springfield, Massachusetts, for an improvement in "Envelop-Sealing Machines," an error appears in the printed specification requiring correction as follows: Page 5, line 1, claim 4, for the word "letter" read *latter*; and that the said Letters Patent should be read with this correction therein that the same may conform to the record of the case in the Patent Office.

Signed and sealed this 16th day of July, A. D., 1918.

[SEAL.]

R. F. WHITEHEAD,
Acting Commissioner of Patents.
